Primary Examiner — Sandra Snapp*Assistant Examiner* — Holly E Thurman(74) *Attorney, Agent, or Firm* — Dennis L. Thomte;
Thomte Patent Law Office LLC(57) **CLAIM**

The ornamental design for an insulated beverage holder dispenser, as shown and described.

DESCRIPTION

This application claims the benefit of Applicant's earlier Non-Provisional Application entitled Insulated Beverage Holder Dispenser, application Ser. No. 14/499,340 filed Sep. 29, 2014.

FIG. 1 is a perspective view of the insulated beverage holder dispenser of this invention;

FIG. 2 is a top view thereof;

FIG. 3 is a front view thereof;

FIG. 4 is a side view thereof;

FIG. 5 is a back view thereof;

FIG. 6 is another side view thereof; and,

FIG. 7 is a bottom view thereof.

The broken lines in the drawings depict items which form no part of the invention.
